UNITED STATES PATENT OFFICE.

JOVAN DROBAC, OF LACKAWANNA, NEW YORK.

RAILWAY-RAIL.

1,211,300.

Specification of Letters Patent. Patented Jan. 2, 1917.

Application filed February 2, 1916. Serial No. 75,815.

To all whom it may concern:

Be it known that I, JOVAN DROBAC, a subject of the Emperor of Austria-Hungary, residing at Lackawanna, in the county of Erie and State of New York, have invented new and useful Improvements in Railway-Rails, of which the following is a specification.

This invention relates to improvements in means for connecting the meeting ends of railway rails, and the object of the invention is to construct the ends of two rails in such a manner as to provide an interlocking engagement between the same so that the said rails will be prevented from independent lateral movement but will be permitted a limited movement in a longitudinal direction.

With the above and other objects in view, the improvement resides in the construction, combination and arrangement of parts set forth in the following specification and falling within the scope of the appended claim.

In the drawings: Figure 1 is a perspective view of two rails constructed and connected in accordance with the present invention. Fig. 2 is a central vertical longitudinal sectional view through the same, Fig. 3 is a transverse sectional view approximately on the line 3—3 of Fig. 1, Fig. 4 is a perspective view of one of the rail ends, Fig. 5 is a similar view of the end of the other rail, and Fig. 6 is a horizontal sectional view taken approximately centrally through the lead portions of the connected rails.

In the drawings, the numerals 1 and 2 designate two rails and 3 the ties upon which the rails rest. The rails 1 and 2 are of the ordinary construction and the rail 1 has one of its ends provided with a web extension 4 that enters the head of said web or in other words the portion 4 of the web is of a greater height than the web proper, the upper edge of the same terminating a suitable distance below the bearing surface of the head of the said rail 1. The upper edge of said extension 4 is horizontally straight, and the same is formed at its upper corner with a nose 5. The nose is flat in plan and has its edges of an arcuate formation, the said edges projecting laterally beyond the

sides of said extension 4. The flange 6 of the rail 1 is formed with a reduced extension 7, the same terminating in a laterally extending nose 8, and this nose has its opposite edges curved, the said nose being disposed directly below the nose 5, so that the web extension 4 is provided with spaced parallel lateral extensions.

The rail 2 has its web cut at a suitable distance from its end providing the same with a vertically straight shoulder 9, the flange of the said rail 2 having a rounded opening 10 to receive the nose 8 of the rail 1, the reduced portion provided by the opening receiving the flanged extension 7 of the said rail 1. The underside of the head of the rail 2 is formed with a pocket 11 which has its side walls rounded, and which is adapted to receive the nose 5, a restricted passage 12 entering from the end of the head of the rail 2 to the said pocket 11 to receive the portion of the web extension 4 between the nose 5 and the end of the head of the rail 1. The pocket and opening in the rail 2 is arranged to have the walls provided thereby engage with the side walls of the nose members of the rail 1 to hold the rails against independent lateral or side movement when assembled, but a limited longitudinal movement is permitted to allow for the expansion and contraction of the rails. The engaging ends of the rails rest upon one of the ties 3 and with a construction as above described, it will be noted that the employment of splice bars or other connecting means is dispensed with. It is, of course, to be also noted that the depth of the pocket 11 corresponds with the thickness of the nose 5 so that the heads of the rails 1 and 2 will be maintained in proper alignment when assembled.

Having thus described the invention, what I claim is:

In a rail joint, two rails, one having a web extension which has its upper edge horizontally straight, said web extension from its upper corner being formed with a nose which is flat in plan, the flange of the rail being formed with an extension terminating in a nose disposed below the first mentioned nose, the other rail having its flange and head

extending beyond the web portion, said flange at its end formed with a vertical opening to receive the web extension of the first mentioned rail, the web being cut to receive the extension of the first mentioned rail, the underface of its head being formed with a pocket to receive the first mentioned

nose, the extension of the flange of the first mentioned rail being provided with an opening to receive the second mentioned nose to prevent lateral movement of the rails when assembled. 10

In testimony whereof I affix my signature.
JOVAN DROBAC.
